Bassett and Harding

ATTORNEYS.

UNITED STATES PATENT OFFICE

WILLIAM ROY HUNTSMAN, OF BROOKLINE, PENNSYLVANIA, ASSIGNOR TO B. B. T. CORPORATION OF AMERICA, OF PHILADELPHIA, PENNSYLVANIA, A CORPORATION OF DELAWARE

BEACON

Application filed March 29, 1928. Serial No. 265,556.

This invention relates to a beacon arranged to throw a beam or beams of light for the guidance of aeroplanes or other air vehicles and is particularly directed to a beacon 5 which serves to send predetermined signals, visible to the operator of an aeroplane.

In beacons heretofore used, the beams of light thrown therefrom have been substantially circular in cross section so that an 10 aviator might readily fly either above or below the beam without seeing the source of light. Furthermore, merely seeing a source of light is insufficient, since such light would convey no information concerning its location or the direction of flight.

It is accordingly the object of the present invention to provide a beacon which will throw a beam of light in a vertical plane so that an aviator intersecting that plane in 20 any position will be able to see the light. A further object is the provision of a beacon which is arranged to give predetermined signals by making visible to an aviator intermittent flashes of light.

25 In the drawing:

Fig. 1 is a side elevation partly in section showing a preferred embodiment of the invention; and

Fig. 2 is a plan view partly in section of the 30 beacon shown in Fig. 1.

A housing 2 is mounted on a vertical shaft 4 which may be driven at any desired speed by a motor, or the like, to cause a rotation of the housing and its contents. Mounted in the 35 housing 2 are a plurality of lamps 6 adjacent each of which are side shields 8 extending outwardly from the body of the housing and providing a passage through which the rays from the lamp may pass. Extending 40 between the shields 8 is a lens 10 which in a vertical plane subtends approximately ninety degrees from a horizontal to a vertical position about the lamp. As shown in Fig. 1, the rays of the lamp may pass through this 45 lens 10 so that the resulting beam subtends an angle of about ninety degrees measured from the horizontal. In transverse cross section lens 10 is shaped so that the diverging rays from the filament of lamp 6 are directed in parallelism therefrom. Secured be-

hind and below lamp 6 is a reflecting mirror 12 substantially concentric with the filament in the lamp, so that the rays passing from the filament are reflected substantially through the filament or closely adjacent thereto and 55 thence outwardly from lens 10. As a result of the construction disclosed, a beam of light extends from each lamp of the beacon, which beam subtends vertically an angle of substantially ninety degrees and which is contained between the parallel vertical planes of shields 8.

By the construction described, it is clear that an aviator cannot intersect the vertical plane of the beam from a lamp on the side of 65 the beacon on which the lamp is located without being able to see the lamp.

If, with all the lamps lighted and in position, the beacon is rotated, a series of intermittent flashes occurring at equal intervals 70 will be visible to a stationary or slowly moving observer. If, instead of having all the lamps lighted, say one of them is removed or turned out or covered so as to be obscured, there will result three intermittent flashes at 75 close intervals followed by a relatively long interval. By other combinations of lighted lamps, it will be clear that various signals may be sent. While only four lamps are shown in the beacon illustrated, it will, of course, be clear that any number of lamps 80 may be provided whereby more elaborate messages may be sent to an aviator or other observer. Also, instead of having the lens equally spaced about the beacon they might 85 be unevenly spaced so that all the lights might be lighted but nevertheless an irregular series of flashes will be produced. It will also be obvious that instead of a series of lamps a single lamp might have its rays directed from a number of apertures, thereby 90 producing the same result.

What I claim and desire to protect by Letters Patent is:

1. A beacon arranged to throw a beam of 95 light subtending vertically an angle of substantially ninety degrees and of relatively narrow horizontal extent comprising a casing, a source of light of relatively small extent carried by the casing, a plurality of 100

parallel vertical masking walls on opposite sides of the source of light and a lens mounted between the planes of the walls and extending about a horizontal axis through the light through substantially ninety degrees, said lens serving to direct rays from the source parallel to the planes of the walls.

2. A beacon arranged to throw a beam of light subtending vertically an angle of substantially ninety degrees and of relatively narrow horizontal extent comprising a casing, a source of light of relatively small extent carried by the casing, a plurality of parallel vertical masking walls on opposite sides of the source of light, a lens mounted between the planes of the walls and extending about a horizontal axis through the light through substantially ninety degrees, said lens serving to direct rays from the source parallel to the planes of the walls, and a concave spherical mirror arranged concentrically with the source on the side opposite the lens.

In testimony of which invention, I have hereunto set my hand, at Philadelphia, Pennsylvania, on this 21st day of March, 1928.

WILLIAM ROY HUNTSMAN.
